Inventor:

Humphrey C. Tiffany
By *Donald R. Dickey* Attorney

UNITED STATES PATENT OFFICE.

HUMPHREY C. TIFFANY, OF DETROIT, MICHIGAN.

PRINTING POSTERS.

Application filed March 20, 1922. Serial No. 545,245.

To all whom it may concern:

Be it known that I, HUMPHREY C. TIFFANY, a citizen of the United States of America, residing at Detroit, in the county of Wayne and State of Michigan, have invented certain new and useful Improvements in Printing Posters, of which the following is a specification, reference being had therein to the accompanying drawings.

In printing large bill posters such as generally displayed on large street and road signs, it is the usual practice to use a plurality of printing plates or blocks, the combined area of which will correspond to the poster to be printed, and very often it is necessary to change one of the plates or blocks. For instance, the maker of an automobile may resort to sign board advertising and have posters printed for different localities or territories, with the posters of each locality or territory provided with the name and address of the automobile distributor or agent. For one style of poster, when universally displayed, it may be necessary to provide a great many printing plates or blocks containing the names and addresses of distributors and after such blocks are used they are generally discarded and cannot be conveniently used for any other purpose. This contributes to the high cost of poster printing and as far as I am aware no other system of printing such large posters has been employed. To reduce this expense, however, some advertisers have provided special labels that may be pasted on the large posters but such labels ordinarily require individual printing blocks and the paste destroyed the general appearance of a high class poster.

My invention aims to obviate the necessity of providing special printing plates or blocks for the production of large bill posters; to eliminate the waste and expense incident thereto, to obviate the necessity of providing special labels or posters for changing parts of a bill poster, and to provide a font of type blocks which will permit of selected blocks being assembled to make up the equivalent of what has been heretofore placed on a single plate or block. In other words, instead of using a one-piece block or etched zinc plate to produce a portion of a sign, I use a plurality of type blocks or plates that may be assembled according to the portion of the sign to be produced, and after such individual plates

or blocks have been used in an assembled form, such form can be knocked down and the individual plates or blocks preserved for future use in connection with the same or other printing of bill posters.

Other advantages of my invention will be apparent to those skilled in the art of printing large posters and in order that my invention may be understood, it will be hereinafter more fully described by aid of the accompanying drawing, wherein—

Figure 1 is a front elevation of a bill poster having a blue background on white paper with the characters of the sign in the natural color of the paper, and indicating by cross hatching the manner in which the printing may be accomplished by using a plurality of blocks to provide overlapped ink portions; 75

Fig. 2 is a plan of an incised type block in accordance with this invention;

Fig. 3 is a cross sectional view of the same, and

Fig. 4 is an enlarged front elevation of a portion of a poster showing how the individual type blocks may produce a portion of a poster. 80

In Fig. 1 I show a large bill poster as having a wide border 1, a blue background 2 and reading matter 3 corresponding in color to the white border 1 or the color of the paper or material on which the bill poster is printed. 85

My invention aims to provide a font of type blocks, one of which is shown in Figs. 2 and 3 and designated 6, and the result of using type blocks in accordance with my invention has been shown in Fig. 4, wherein I have employed dash lines to indicate the printing performed by the individual blocks. 90

Each block may be made of wood, metal, composition or any suitable material in which may be molded or otherwise formed 100 a character 7. The font of such type blocks will necessarily include all of the characters of the alphabet and such punctuation marks, abbreviations, symbols and indicia as may be common in the make up of various kinds 105 of bill posters.

The type blocks can be easily placed side by side when properly selected to make up a portion or panel 4 of the sign and said blocks may have the side walls thereof finished true for perfect abutting relation so 110 that the selected blocks may be suitably

- clamped together and held for printing purposes. With the blocks securely clamped together it will be practically impossible to note, on a printed poster any demarcations or indications of adjoining blocks having been used, and the panel formation of blocks is so proportioned that when printing the panel 4 portions of the blocks will overlap the background 2 of other poster panels.
10. As an instance of such overlapped printing see Fig. 4 where the background has been shaded to indicate heavier printing, as at 8, but since such printing is in one color it cannot be detected at a distance even 15 though a shade darker than the background or body of the poster.

A prescribed number of posters having been printed with a desired panel the type blocks may be knocked down and if necessary, used to form another sign or produce other panels, consequently the type blocks may be repeatedly used for producing different signs in connection with the general poster. It is also obvious that a font of type 25 blocks in accordance with my invention will at all times be convenient for printing any poster; that there is no waste of wood or material due to type blocks being discarded, and in consequence of the time saved in 30 carrying large blocks and the material entering into such blocks there is a great saving in the cost of printing bill posters.

My method of printing differs from the ordinary type of plates insomuch that I use individual reverse characters or the like for imprinting and it is believed that such individual type blocks can only be advan-

geously used on posters, observed from a distance, from where slight imperfections that might occur cannot be detected. In other 40 words, the background of a poster is sufficient to practically obliterate any fine lines or demarcations that may result from adjoining type blocks and since I gain distinct advantages over the present system of printing posters, I desire to be understood that my invention is not necessarily limited to materials entering into the type blocks, but may include all such ramifications of my invention as fall within the scope of the appended claim, for instance a zinc plate containing a single etched character or the like may be mounted on a block, cylinder or other holder so that it may be again used and thus fulfill practically the same purpose 50 as though the block of wood were used for an imprint.

What I claim is:

In the art of printing large posters having a solid color background by individual 60 blocks adapted to print a portion or panel of the poster; means for printing such panels comprising incised interchangeable blocks, the printing surfaces of which form a common background for ink adapted to 65 produce the color background of the poster, certain of said interchangeable blocks adapted to imprint over the margins of the background, formed by adjacent blocks so that there are overlapped ink portions, adjacent each panel obliterating any line demar- 70 cation between panels.

In testimony whereof I affix my signature.

HUMPHREY C. TIFFANY.
